INVENTOR:
Rudolph Claus,
by John Howard McElroy, his Atty

UNITED STATES PATENT OFFICE.

RUDOLPH CLAUS, OF OTTAWA, ILLINOIS.

BACK-REST.

1,322,292.

Specification of Letters Patent.

Patented Nov. 18, 1919.

Application filed August 15, 1919. Serial No. 317,645.

To all whom it may concern:

Be it known that I, RUDOLPH CLAUS, a citizen of the United States, and a resident of Ottawa, in the county of La Salle and State of Illinois, have invented certain new and useful Improvements in Back-Rests, of which the following is a full, clear, and exact specification.

My invention is concerned with back rests for automobile seats, etc., and is designed to produce a simple back rest of an attractive appearance which can be placed in the seat when needed, as for instance where a short-legged person is driving a machine, so as to furnish a perfect support for his back and still leave him in the proper position to manipulate the steering wheel and operate the various foot pedals.

To illustrate my invention, I annex hereto a sheet of drawings in which the same reference characters are used to designate identical parts in all the figures, of which

Figure 1 is a perspective view of a back rest embodying my invention;

Fig. 2 is a central vertical section through the same; and

Fig. 3 is a horizontal section on the line 3—3 of Fig. 2.

In carrying out my invention, I make up a three part covering consisting of the back part *a*, the front *b* and the bottom *c*. These pieces are made of any desired flexible material, preferably leather, or imitation leather, and the back part *a* has a straight bottom and a curved side and top. The front part *d* is of the same general design, except that it is narrower, and the bottom part *c* is crescent shaped. In manufacturing the cushion, I sew the edges of the sides and top of both the pieces *a* and *b* together on a machine, and I also sew the bottom of the front piece to the bottom piece, and all of the bottom of the back piece to the bottom piece except the part between the points *d* and *e*, which is left open, so that the parts, so far sewed together with the wrong side out, can be inverted and so that the stuffing and the stiffening back piece can be inserted. The stiffening back piece

f is of the same general shape as the back cover part *a*, except that it is slightly smaller, and it is made of some material capable of being flexed without breaking, such for instance as rag board, which can be rolled up sufficiently so that it can be inserted in the unsewed space between the points *d* and *e*,

and then allowed to unroll within the covering so as to occupy the position shown in Figs. 2 and 3, where it is held in the curved shape shown by reason of the fact that the front part *b* is narrower than the back part *a*. After this stiffening back piece *f* has been inserted, a suitable quantity of filling *g*, which I preferably form of a fine grade of wood wool is inserted through the aperture left in the bottom, until the desired amount is employed, after which the open space between the points *b* and *e* is sewed up by hand. The parts are then secured together and given the desired tufted form by passing the threads *h* through the back piece *a*, the stiffening back board *f*, the stuffing *g* and the front piece *b* and securing them to the customary tufting buttons *j* in the customary manner.

The resulting cushion is a durable one, attractive in design, and which furnishes a perfect support for the back, as described.

While I have shown and described my invention as embodied in the form which I consider best adapted to carry out its purpose it will be understood it is capable of modifications, and that I do not desire to be limited in the interpretation of the following claims, except as may be necessitated by the state of the prior art.

What I claim as new and desire to secure by Letters Patent is:

1. As a new and useful article of manufacture, a back rest consisting of a stiffening back piece composed of a stiff material capable of being flexed without breaking, a flexible front piece narrower than the back piece and co-operating therewith to hold the latter curved in horizontal cross-section, a bottom piece connecting the front piece and extending beyond the stiffening back piece, stuffing between said front and back pieces, and tufting members passed through the back piece, stuffing and front piece to make a concave front on said rest.

2. As a new and useful article of manufacture, a back rest consisting of a three piece flexible covering member, consisting of a back part and front part sewed together at their sides and tops, and a bottom part sewed to the bottoms of the back and front parts, a stiffening back piece composed of a stiff material capable of being flexed without breaking resting against the back part, stuffing between the stiffening back piece and the front part, and tufting members

passed through the back part, stiffening back piece, stuffing and front part to make a concave front on said rest.

3. As a new and useful article of manufacture, a back rest consisting of a three piece flexible covering member, consisting of a back part having a curved top and sides and a straight bottom, a flexible front covering of the same shape but narrower sewed to the back at its sides and tops, a crescent shaped bottom piece sewed to the bottom of the back and front coverings, a stiffening back piece composed of a stiff material ca-

pable of being flexed without breaking and of the same shape and substantially the same size as the back covering part, stuffing between the stiffening back piece and front covering part, and tufting members passed through the back covering part, the stiffening back piece, stuffing and front covering to make a concave front and a stiff convex back for said rest.

In witness whereof, I have hereunto set my hand and affixed my seal, this 5th day of August, A. D. 1919.

RUDOLPH CLAUS. [L.S.]
